ENGINE

Charles N. Kahl, Jacksonville, Ill., assignor of one-half to Lee A. Sullivan, Jacksonville, Ill.

Application August 28, 1944, Serial No. 551,496

1. Claim. (Cl. 123—65)

This invention relates to improvements in two-cycle engines employing a turbine-driven supercharger, and is a continuation-in-part of my co-pending applications Serial No. 401,243 filed July 5, 1941, and Serial No. 448,989 filed June 29, 1942, both for Engines.

In the ordinary two-cycle engine only a single exhaust port is provided in each cylinder as a means to perform the dual function of pressure exhausting and scavenging. Turbine-driven superchargers cannot be successfully operated in conjunction with two-cycle engines having such a single exhaust port because the back pressures formed by the turbine-driven supercharger interferes with proper evacuation of exhaust gases. The cool air forced into the cylinder through the intake valve mixes and cools the residual gases remaining in the cylinder after the high pressure gas has escaped through the exhaust port. Such cooled gases adversely affect the operation of the turbine-driven supercharger because such admixture of cooled gases is forced into the supercharger and, therefore, lowers the temperatures therein.

It was to overcome this and other disadvantages accruing in a single exhaust ported two-cycle engine employing a turbine-driven supercharger that the present invention was conceived.

The main objects of this invention are to provide an improved and more efficient two-cycle engine employing a turbine-driven supercharger; to provide such an engine wherein each cylinder therein includes a high pressure exhaust port whereby to allow the high pressure gases only in the cylinder to be evacuated therefrom and therethrough; to provide a high pressure exhaust port in each cylinder of such an engine whereby the products of combustion are evacuated from the cylinder at their highest temperature and a low pressure exhaust port in each cylinder for scavenging; to provide an engine of this character wherein back pressures are eliminated because of provision being made for the opening and the closing of a high pressure exhaust port independently and exclusively of the opening and closing of the low pressure exhaust port, whereby the complete cycle of opening and then closing the high pressure exhaust port is effected before the other is opened; to provide an engine of this character wherein each of the cylinders is provided with a high pressure exhaust port which is adapted to open and expel the high power exhaust gases from the cylinder and then be closed before the intake port and scavenging port are opened; to provide an engine of this character

wherein the efficiency of the supercharger is greatly increased because the exhaust gases are expelled from the cylinder at a higher temperature through a high pressure exhaust port and delivered to the supercharger before they have had an opportunity to become cooled; to provide an engine of this character wherein approximately 70% to 80% of the products of combustion formed in the cylinder on each stroke is exhausted directly to a supercharger and then the exhaust port closed before the intake port and scavenging port are opened; and to provide an engine of this character which is simple in construction and more efficient in operation.

15 An illustrative embodiment is shown in the accompanying drawings in which:

Figure 1 is a vertical cross-sectional view through a cylinder embodying a construction in accordance with my invention and showing the piston at the bottom dead center of its stroke; the intake port and the scavenging port being open.

Fig. 2 is a view similar to Fig. 1 but showing the piston starting on its upstroke with all the ports closed.

Fig. 3 is a view similar to Fig. 1 but showing the piston at the upper end of its stroke, the ports all closed and the arrows indicating emission of the fuel into the upper end of the cylinder.

30 Fig. 4 is a view similar to Fig. 1 showing the piston on its down stroke with ports all closed.

Fig. 5 is a view similar to Fig. 1 showing the piston continuing on its down stroke, the high pressure exhaust being opened and the other ports being closed.

35 Fig. 6 is a diagrammatic representation illustrating the various positions of the piston and piston sleeve during a complete 360° rotation of the crankshaft with respect to their various positions to the three ports in the cylinder.

40 Referring in detail to the drawings, the engine block or frame 1 contains the usual water jackets 2 for the cylinder 3, air passageways or chambers 4, an exhaust port 5, hereinafter referred to as the low pressure exhaust port, and an intake port

45 6. In addition to the above I have added a high pressure exhaust port 7 located between the intake port 6 and the low pressure exhaust port 5, the purpose of which will be hereinafter explained.

Each cylinder 3 contains a piston 8, of the type disclosed in my two above referred to co-pending applications, which is provided with a roller bearing 9 designed and arranged for coaxing engagement with the cam track 10 of the wobble cam

11. A reciprocating valve sleeve 12, of the character disclosed in my above referred to co-pending application Serial No. 448,989, encompasses the piston 8 and lines the cylinder walls.

The sleeve 12 is provided with a roller bearing 13 for coactive engagement with the sleeve track 14 of the wobble cam 11, and a series of ports 15 and 16. As fully explained in my aforesaid co-pending application Serial No. 448,989, the valve sleeve 12 is designed to travel slightly 5 ahead of the piston travel regardless of the direction of travel of the piston 8 (upstroke or downstroke) because the sleeve track 14 leads the piston track 10 by a few degrees.

A supercharger turbine (not shown) is arranged to be connected to the high pressure exhaust port 7 in the usual and same manner as a 15 supercharger is connected to the usual exhaust port; hence it is not necessary to illustrate the same.

A complete cycle of operation of this engine is comprehensively shown in the drawings Figures 1 to 5. In Fig. 1, the piston is at its bottom dead center; hence the intake port 6 and the port 15 are in registry with each other and air forced 25 into the cylinder. At the same time the low pressure exhaust port 5 and the port 16 are in registry with each other and scavenging of the low powered exhaust gases is taking place; that is, the fresh air forces the remaining burned gases 30 from the cylinder. It is to be noted that the high pressure exhaust port 7 is completely closed off from the cylinder.

In Fig. 2 the piston is on its upstroke, as is the valve sleeve 12; therefore, the ports 15 and 16 35 are out of registry with the low pressure exhaust port 5, the intake port 6, and high pressure exhaust port 7.

In Fig. 3 the piston has reached the top of its upstroke as has the valve sleeve 12, and as shown 40 therein, the ports 15 and 16 are out of registry with the low pressure exhaust port 5 and intake port 6. The piston being at the top of its stroke, fuel is automatically injected into the top of the cylinder through the fuel nozzle 17 and the hot gases expand against the piston forcing it downward on the power stroke.

In Fig. 4 the piston has started on its downward stroke and it is to be noted that all of the 45 ports are out of registry with the sleeve ports.

In Fig. 5 the piston is still on its downstroke and the top thereof is approximately opposite the high pressure exhaust port 7. The valve sleeve 50 has descended to a point whereby the ports 15 are in registry with the exhaust port 7. At this point the high powered exhaust gases rush out of the cylinder through high pressure exhaust port 7 and directly into the supercharger.

As the piston and sleeve descend further, all 55 of the ports will be out of registry until the piston substantially reaches bottom dead center of its stroke, wherein the position of the piston and sleeve will be in the position shown in Fig. 1. There as pointed out heretofore the ports 15 are in registry with the intake port 6 and the ports 16 are in registry with the low pressure exhaust port 5.

This cycle of operation is diagrammatically shown in Fig. 6 and thoroughly illustrates the 60 reason why the high pressure exhaust port is only in registry with the ports 15 on the downstroke of the piston. It will also be seen that the high pressure exhaust port is opened to the cylinder only a fraction of the length of time the intake port and the low pressure exhaust port 65 75 70 75

are opened for the purpose of scavenging and admitting fresh air to the cylinder.

Therefore, it should be readily apparent that only the high temperature exhaust gases are evacuated from the cylinder through this port. These gases are fed directly into the supercharger turbine before the burned gases have had an opportunity to become cooled by the admission of air into the cylinder. Such being the case, the exhaust gases are fed into the supercharger turbine at substantially the existing temperatures of the gases at the time of uncovering the port. The supercharger, therefore, having had no opportunity to become cooled by the admission of lower temperature gases or gases mixed with cool air, will operate at greater increased efficiency. Since there is no communication between the high pressure exhaust and the scavenging exhaust or the air intake, back pressure from the supercharger cannot impede either scavenging or intake charging.

Since the supercharger is provided with exhaust gases at abnormally high temperatures (even up to 1700° F. and pressures to 200 pounds) greater power is developed in the turbine-driven supercharger than is required for scavenging and supercharging. It is readily apparent that this power may be efficiently fed back to the engine drive shaft through suitable gearings and hydraulic couplings as will be readily understood by those skilled in this art.

It should also be apparent to those skilled in the art that approximately 70° to 80° of the products of combustion formed in the cylinder on each stroke may be exhausted directly to the supercharger by employing the construction illustrated.

As will be seen from Fig. 6 on the upstroke of the piston 8 and the sleeve 12 after they each reach bottom dead center, (the piston at 180° and the sleeve at 188°) the sleeve travel will be slightly behind the piston travel; therefore, the intake port will be opened a short period of time after the top of the piston has reached a point opposite the upper edge of the intake as the ports 15 in the sleeve will only be substantially half closed. The air flowing in the cylinder through the intake port will, of course, be of diminished quantities, until the sleeve 12 completely covers the intake port 6.

It is to be understood that the piston covers sleeve port 15 before the port 15 registers with or passes the high pressure exhaust port 7.

By this procedure it is apparent that more air is forced and packed into the cylinder than was possible heretofore because this additional air is admitted to the cylinder after the scavenging or low pressure port 5 has been closed as the port 16 has moved out of registry with the port 5.

It is to be understood that numerous details 60 of the construction shown and described may be altered or omitted without departing from the spirit of this invention as defined by the following claim:

I claim:

In an engine of the class described comprising a cylinder, a piston in said cylinder, a valve sleeve in said cylinder positioned between said piston and the walls of said cylinder and having axially spaced upper ports therein located adjacent the upper end of said sleeve, axially spaced lower ports located adjacent the lower end of said sleeve, a low pressure exhaust port in one end of said cylinder, an intake port in the other end of said cylinder, a high pressure exhaust port in said cylinder located between said low pressure ex-

haust port and said intake port, and means for reciprocating said sleeve whereby said high pressure exhaust port communicates with the interior of said cylinder through the lower port in said sleeve on the power stroke only of the piston and while the low pressure exhaust port and the intake port are closed off from the interior of

said cylinder, said ports in said sleeve substantially simultaneously register with said low pressure exhaust port and said intake port for communication with the interior of said cylinder towards the end of the power stroke of said piston, and while said high pressure exhaust port is closed.

CHARLES N. KAHL.
